Primary Examiner — Dana Meyrow*(74) Attorney, Agent, or Firm* — Tommy SF Wang; Wang IP Law Group, P.C.(57) **CLAIM**

The ornamental design for a bottle, as shown and described.

DESCRIPTION

FIG. 1 is a perspective view of a bottle showing my new design;
FIG. 2 is a front view thereof;
FIG. 3 is a top view thereof;
FIG. 4 is a bottom view thereof;
FIG. 5 is another perspective view thereof, with a cap of the bottle shown in a detached configuration; and,
FIG. 6 is the other perspective view thereof, with the cap of the bottle shown in the detached configuration.
A rear view, a left side view and a right side view are omitted as they are identical to the front view shown in FIG. 2.
The broken line portions of the bottle in FIGS. 1-2 and FIGS. 4-6 represent unclaimed portions of the claimed design and form no part thereof.
